(57) **CLAIM**

The ornamental design for a power adapter as shown and described.

DESCRIPTION

FIG. 1 is a perspective view of a first embodiment of a power adapter showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the first embodiment of the power adapter where the power adapter is in a configuration of use;

FIG. 10 is a perspective view of a second embodiment of the power adapter;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is a perspective view of the second embodiment of the power adapter where the power adapter is in a configuration of use;

FIG. 19 is a perspective view of a third embodiment of the power adapter;

(Continued)

FIG. 20 is another perspective view thereof;
 FIG. 21 is a front elevational view thereof;
 FIG. 22 is a rear elevational view thereof;
 FIG. 23 is a left side elevational view thereof;
 FIG. 24 is a right side elevational view thereof;
 FIG. 25 is a top plan view thereof;
 FIG. 26 is a bottom plan view thereof; and,
 FIG. 27 is a perspective view of the third embodiment of the power adapter where the power adapter is in a configuration of use.
 The broken lines in the drawings are for the purpose of illustrating portions of the power adapter that form no part of the claimed design.
